UNITED STATES PATENT OFFICE

167,311

TILE

Eleonore Hambuechen, Huntington, N. Y.

Application March 11, 1952, Serial No. 18,848

Term of patent 3½ years

(Cl. D18—2)

To all whom it may concern:

Be it known that Eleonore Hambuechen, a citizen of the United States, residing at Huntington, in the county of Suffolk and State of New York, has invented a new, original, and ornamental Design for a Tile, of which the following is a specification, reference being had to the accompanying drawing, forming part thereof.

In the drawing the figure is a plan view of a tile showing my new design.

I claim:

The ornamental design for a tile, as shown.
ELEONORE HAMBUECHEN.
